METHOD OF PRINTING NAMES ON CARDS

Clarence H. Freund, Wilmette, Ill., assignor to Clarence H. Freund, Irene Freund, John W. Walz, and Agnes Loretta Walz, copartners, doing business as Nu-Art Engraving Company, Chicago, Ill.

Application April 11, 1946, Serial No. 661,265

4 Claims. (Cl. 101—426)

1

The invention relates to printing generally and more particularly to the printing of names or other data on previously printed cards or sheets.

Certain types of printed items such as advertising folders, calendars, greeting cards, etc. are commonly distributed in relatively small lots, each of which has a different name or other data printed thereon. As most of the printed matter on such items is the same, the items are usually produced in large quantities and the individual data or name lines for each lot are printed thereon in a separate operation. With the printing equipment heretofore available this procedure necessitates changing the setup of the press for each lot, thereby substantially decreasing the productive capacity of the press which together with the additional labor involved materially increases production costs.

As it is usually necessary to print the individual names or data at definite locations on the previously printed item a further difficulty is encountered where items of different sizes or having different arrangements of printed matter are involved. Thus the printing of name lines on greeting cards presents a particularly complicated problem, as such cards are commonly produced in varied sizes and with widely different arrangements of the printed matter and designs. This, of course, necessitates a change in the location of the name for each size of card. In accordance with present practice a complete change of the press setup is made for each lot of cards and the cost of the cards is correspondingly increased.

With the foregoing in view, the primary object of the present invention is to provide an improved method of and apparatus for setting up a press to print name lines on cards or the like by which the difficulties above mentioned are eliminated, thus enabling small lots of cards or sheets of varied sizes and makeups to be printed rapidly and at relatively low cost.

A more specific object is to provide an improved method of and apparatus by which the setup of the press may be changed to accommodate cards or sheets of different sizes and widely varying makeups with a minimum of manual labor and with little loss of time, thus increasing the productive capacity of the press and substantially reducing the labor costs of the printing operation.

Another object is to provide an improved chase assembly for printing presses which greatly facilitates the changing and accurate location

2

of the type used in printing name lines or other data on previously printed cards or sheets.

Other objects and advantages of the invention will become apparent from the following detailed description of the preferred embodiment illustrated in the accompanying drawings in which:

Figure 1 is a fragmentary perspective view of a printing press equipped with a chase assembly adapted to be set up for printing names or the like on previously printed cards in accordance with the improved method contemplated by the present invention.

Fig. 2 is a fragmentary view of the chase assembly.

Fig. 3 is a perspective view of a filler for use in carrying out the improved method.

Fig. 4 is a perspective view of a clamping device for retaining a type slug in set position in a chase of the type shown in Fig. 2.

Fig. 5 is a diagrammatic view showing the manner in which sheets of different sizes and having different makeups are presented to the chase for printing.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

To illustrate the invention, I have shown in Fig. 1 of the drawings the essential elements of a conventional vertical job press set up for printing individual names on greeting cards. Presses of this type are equipped with a vertically reciprocable bed to which a rectangular type holding frame or chase 10 is secured in any suitable manner for reciprocation with the bed. The cards to be printed are presented to the chase

by a rotatably driven cylinder 11 which receives the cards from the usual feed board 12. In the particular press shown, the cards are delivered to the feed board automatically by a pneumatic picker 13 which is oscillated in well known manner in timed relation to the reciprocation of the press bed. In each cycle of the bed the picker removes a card from a stack 14 carried by a vertically shiftable feed table 15 and deposits the card on the feed board 12 from which it is picked up by the cylinder 11 for presentation to the

chase. The table 15 is automatically raised step-by-step as the cards are removed therefrom.

In order to locate the cards in proper relation to receive the imprint from the type carried by the chase 10 a guide member 16 is provided for cooperation with one side edge of the card as it is deposited on the feed board 12. The guide member 16 is adjustably mounted on a horizontal rod 17 supported above the feed board 12 by a pair of crank arms 18 mounted on the machine frame. The crank arms also carry the usual side guide rod 19 which in this instance has its central portion 20 offset laterally from the axis of the rod to provide convenient access to the chase for reasons that will appear presently. Provision is made for rocking the crank arms 18 in timed relation to the oscillation of the picker 13 to enable the latter to deposit the cards on the feed board 12 without interference.

The table 15 is likewise provided with suitable guide members 21 and 22 for locating the card stack 14 with respect to the feed board. The guide members as herein shown comprise angle bars extending vertically along the rear edge of the table and adjustably supported at their lower ends on the press frame. In practice the guide member 21 is normally secured in a fixed position as by a clamping bolt 23 while manually operable means indicated generally at 24 is provided for effecting rapid adjustment of the guide 22 to accommodate cards of different lengths. In other words, the stop members 16 and 21 remain stationary during normal printing operations and thus provide a fixed reference point for the presentation of cards to the chase.

In carrying out the invention, the chase 10 is provided with furniture for the accommodation of standard "linotype" slugs 24 and arranged to permit quick interchange of the slugs and their accurate location in predetermined printing positions without requiring removal of the chase from the press or in any way disturbing the chase assembly. For this purpose a plurality of relatively thin, elongated flat bars 25 are arranged horizontally in the chase with spacing elements 26 interposed between adjacent bars. Two of the spacing elements 26 are provided between each pair of the bars 25 and the elements are located adjacent opposite ends of the bars so as to form therewith a series of parallel slots 27 extending transversely across the chase. Sufficient bars are installed to provide the desired number of slots and the remaining space of the chase is filled with conventional spacing elements 28 and the entire assembly is locked in place by suitable quoins or wedges 29.

In the exemplary chase assembly, the spacing elements 26 are of substantially the same thickness as the type slugs 24, thus spacing the bars 25 apart so that the type slug may be easily inserted in or removed from the slots 27. To provide for varying the position of the type slug transversely of the chase the elements 25 are spaced apart a substantially greater distance than the length of the type slugs or, in other words, the slots 27 are made longer than the slugs.

Suitable means is provided for frictionally clamping the type slug in adjusted position in the slot in which it is inserted. As herein shown, the clamping means comprises an elongated flat spring member 30 adapted to be inserted in the slot adjacent the one containing the type slug. The spring member is preferably bowed in one direction substantially at its center and in the

opposite direction adjacent opposite ends as shown in Fig. 4 so that when inserted in a slot 27 a substantial clamping pressure is exerted on the bars defining the slot. The ends of the spring member may be notched to provide projecting lugs 31 for engagement by a hook or other suitable tool for convenience in removing the member from the slot.

In setting up the printing apparatus to print 10 different names or other data on small lots of cards or sheets of varied sizes and makeup, an especially advantageous method or procedure is employed. First a chase assembly of the character above described or other suitable type holding means, having a plurality of vertically aligned slots for the accommodation of type slugs is secured to the bed of the press. The slots are identified by suitable indicia as, for example, numerals applied in any preferred manner to the spacers defining the slots.

20 The feed mechanism of the press is adjusted so as to present all cards or sheets to be printed to the chase in the same relative position, that is, in a definite fixed relation with respect to the vertical spacing of the slots and in fixed relation with respect to the aligned ends of the slots. With this arrangement the printing may be located at any desired position on a card by inserting the type slug in a selected one of the slots and suitably adjusting it longitudinally therein.

25 To facilitate the accurate location of the slug longitudinally of the slot in which it is inserted, a suitable filler 33 is inserted in the slot in abutting relation with the type slug and the vertically aligned end of the slot. In practice the printer setting up the press is supplied with a plurality of such fillers of progressively varying length corresponding to the spacings required for the different classes of cards to be printed.

30 Referring to Fig. 3 of the drawings, the filler 33 in its preferred form comprises a flat generally rectangular plate 34 slightly thinner than the type slug 24 so that it will fit loosely in any one of the slots 27. Rigidly secured to one edge of 40 the plate 34 and extending over the same with its free edge spaced therefrom is a resilient spring member 35 adapted to frictionally engage the walls of the slot in which the filler is inserted to hold it securely in place therein. The plate 34 45 may be formed with notches 36 at opposite ends for engagement by a suitable hook or tool for convenience in withdrawing the filler from the slot.

50 As explained above, the slots 27 of the chase assembly, are identified by suitable indicia. The fillers 33 likewise carry suitable indicia as, for example, letters, each individual to a filler of predetermined length. To coordinate this data for the use of the printer, each size or type of card to be printed is identified with a dual designation indicative of the slot in which the type slug is to be inserted and the filler to be used therewith when the card is printed.

55 By way of example it will be assumed that small lots of cards are to be printed with individual names from each of three groups of cards A, B and C which differ from each other in size and makeup or both. The relative positions in which such cards are presented to the chase are shown 60 diagrammatically in Fig. 5. In the drawings the vertical line X represents the reference point for the right-hand edges of the cards as determined by the setting of the guide member 16. Vertical line Y represents the reference points or abutments at the aligned left ends of the slots 27. The

particular cards illustrated are of the type adapted to be folded centrally as indicated by the broken line 40.

In order to locate the name in the desired relation to the bottom edge of the card A, the type slug must be inserted in the slot 8. For centering the name, a filler of a particular length is required which may be conveniently designated as filler D. Accordingly the designation D8 applied to this card will give the printer all information necessary to set up the press for the proper printing of the names on cards A.

The card B as shown is substantially shorter and wider than the card A and the spacing of the name from the bottom is substantially greater. This card may be identified by the reference characters E5 indicating that the type slug is to be inserted in the slot 5 along with a filler E. Likewise card C may be identified by the characters F7 to indicate that a type slug is to be inserted in the slot 7 along with a filler F. Thus a suitably designated filler 33 is provided for and coordinated with a card of each size so that the printer may position the type slug accurately without loss of time and with little effort. As the order is made up for each lot of cards, it may be suitably marked with the necessary identifying data so that no calculations by the printer are required and idle press time is reduced to a minimum.

In actual practice, cards of a single size are usually printed successively so that the only changes necessary between lots of cards of such size is a change of the type slug bearing the name to be printed thereon. Thus, as each order is received, the printer notes the designation, places the proper filler in the proper slot along with the name slug, and places the required number of cards on the feed table of the press. Upon completion of the run, the type slug is interchanged with a slug suitable for the next run, and printing may proceed. When the size of the card is changed, the filler 33 is interchanged with one of the proper dimensions and printing proceeds as before explained. The only press adjustment required by a change of card sizes is a shifting of the guide member 22 which does not in any way affect the delivery of the sheets to the press as this is determined by the location of the fixed guides 16 and 21.

Where more than one line of printed matter is to be applied to a card as, for example, a plurality of names or a name and address, the type slugs are inserted in successive slots one above the other along with the proper fillers. The necessary instructions may be given the printer for this purpose by a suitable designation utilizing the indicia above described.

It will be apparent from the foregoing that the invention provides an improved method and apparatus for setting up printing apparatus to print names on cards or sheets of varied sizes which practically eliminates idle press time and which materially reduces the labor involved in changing the press setup. Due to the novel construction and arrangement of chase assembly, all necessary changes may be made without necessitating removal of the chase from the press. Moreover accurate location of the type for determining the position of the printed matter is greatly facilitated. Small lots of cards or sheets may thus be printed economically and at a rapid rate.

I claim as my invention:

1. The method of setting up apparatus for printing different name lines or other matter on a plurality of groups of cards of varied sizes from type slugs individual to the respective groups 5 which comprises, assembling a chase to provide a plurality of vertically aligned spaced parallel slots adapted to receive the type slugs, identifying each slot with distinctive indicia, preparing a series of fillers of progressively varying length for insertion in said slots with a type slug to determine the position of the slug in the slot, identifying each of said fillers with distinctive indicia, and identifying each group of cards with dual indicia indicative of the particular filler to be used when printing the cards of that group and the particular slot in which the filler and the type slug are to be inserted for such printing.
2. The method of setting up apparatus for printing a line of matter in selected positions on 20 each card of a plurality of groups of cards of different sizes and makeups which comprises, preparing an individual type slug for each group of cards, assembling a chase to provide a plurality of spaced parallel slots for the reception of the 25 type slugs, identifying each slot with indicia corresponding to the position on a card at which a type slug therein will print on a card presented to the chase in a predetermined position, providing a series of fillers of progressively varying 30 length, and identifying each filler with a particular size of card with which it is to be used to center the type slug with respect to the card when presented in said predetermined position.

3. The method of printing name lines or the like in selected positions on cards of different sizes which comprises arranging the furniture in a chase to provide a plurality of vertically spaced parallel slots adapted for receiving type slugs together with fillers of various lengths interposed 35 between the slugs and said ends of the slots, designating each slot and each filler with distinctive indicia, and identifying each size of card with dual indicia indicating the particular slot and filler to be used in printing the name line on the card 40 whereby to facilitate the selection of the slot and filler.

4. The method of printing a line such as a name line on a greeting card or the like which comprises arranging the furniture in a chase to provide a plurality of spaced parallel slots terminating at one end in a common plane and adapted for receiving type slugs together with fillers of various lengths interposed between the slugs and said ends of the slots, designating the slots according to their positions vertically in the chase and the fillers according to their lengths, and identifying each card to be printed with a predetermined one of the slots and a predetermined one of the fillers whereby to facilitate selection of the proper slot to receive the type slug and of the filler determining the transverse spacing of the slug.
